COMPUTING MACHINE

Frederick A. Hart, Stamford, Conn., assignor
to Remington Typewriter Company, Ilion,
N. Y., a corporation of New York

Original application January 21, 1927, Serial No.
162,473. Divided and this application Septem-
ber 26, 1931. Serial No. 565,263

4 Claims. (Cl. 308—189)

My invention relates to computing machines. In these machines there are parts of the mechanism that are required to move with a considerable degree of precision and at the same time, especially in computing machines of that class in which the computing mechanism is operated by the keys of a typewriter, it is necessary that the parts move freely so as to offer as little resistance as possible to the operation of the key. The present invention has for its principal object to improve mechanism of this character in respect to precision of movement and readiness, accuracy and permanency of adjustment, together with freedom of movement; and to attain these objects with mechanism that may be easily and cheaply manufactured.

To the above and other ends my invention consists in certain features of construction and combinations and arrangements of parts, all of which will be fully described herein and particularly pointed out in the claims.

This application is a division of my prior application Serial No. 162,473, filed Jan. 21, 1927.

I have shown my invention applied to a Remington combined typewriting and computing machine, the general construction and mode of operation of which are well-known in the art. For the purposes of the present invention the machine may, if desired, be made as described in the patent to Wahl No. 1,270,471, dated June 25, 1918, except as hereinafter pointed out. In other words, for the purpose of description the invention in the form in which it is set forth herein may be regarded as an improvement in the mechanical structure of the machine described in said patent. In view of what has just been said, the accompanying drawings show only so much of the machine as is necessary to illustrate my improvements.

In said drawings, all of which are more or less fragmentary,

Figure 1 is a front view;

Figure 2, a left-hand end view;

Figure 3, a right-hand view in section on the line 3—3 of Figure 1;

Figure 4 is a section on the line 4—4 of Figure 2 and looking in the direction of the arrow at said line.

Figure 5 is an irregular section approximately on the line 5—5 of Figure 1 and looking downward.

Figure 6 is a section about on the line 6—6 of Figure 1 and looking toward the left.

Figure 7 is a similar view but with some of the parts removed.

Figure 8 is a view in section on the line 8—8 of Figure 7.

Figures 4—8 are on a larger scale than Figures 1—3.

The Remington combined typewriting and computing machine comprises a Remington typewriter having attached thereto computing mechanism of the sort described in the Wahl patent above referred to. The actuator of said computing mechanism comprises a main frame casting 60 10 secured to the top plate of the typewriter and a number of sheet metal frame plates projecting in front and rear planes from said casting.

Seven of said plates are shown in the drawings and designated 11, 12, 13, 14, 15, 16 and 17. 70 Plates 11 and 14 may be regarded as the two end plates of the vertical actuator and these are secured respectively to two forwardly projecting lugs or brackets 18 and 20 integral with main casting 10. Plate 15 is the left-hand end plate 75 of the cross actuator, the right-hand end plate of which is not shown, but in the machine it is supported on the extreme right-hand end of the casting 10. The frame plates 15, 16 and 17 are supported directly or indirectly from plate 14 80 and the right-hand end plate, not shown, the supports consisting of certain cross rods or posts, some of which are shown and lettered 21, 22, 23 and 24. Each of the parts marked 21, 22 and 23 consists of a rod running through all of the 85 plates and having sleeves or bushings strung on it to space the plates apart. The bracket or plate 11 is fastened to the main casting by two screws 25 and plate 14 by two screws 26.

Each of the ten numeral keys of the typewriter has connected thereto a link 27, Fig. 6, which at its upper end is pivoted to a so-called "fan" 28, the hub of which is journaled on a cross rod 30 of the vertical actuator.

Each fan operates a corresponding goose-neck 95 cam which actuates an arm 43 secured to and projecting from a differential rock shaft 44 which is journaled in the frame plates 11 and 14 and which is also supported near its middle where it passes through the plate 13 by three ball-bearing 100 rollers 91, 92 and 93 (Figs. 1, 6, 7 and 8). This differential rock shaft 44 carries the usual peculiar hub structure 45 to which at 46 is pivoted the usual gear sector or segment 47 which operates the vertical master wheel. This gear segment is 105 arranged to act on the down stroke of the key on a drive pinion 48 for addition or on an auxiliary pinion 50 for subtraction, said pinions being in mesh with each other and the former splined on the shaft 51 of the vertical master wheel 52 which 110

drives the so-called carrying wheels 53 of the vertical totalizers, the last traveling back and forth in unison with the typewriter carriage; all of these parts being and operating the same as heretofore.

Journaled in the frame plates 15 and 16 is the differential shaft 54 of the cross footer on which the gear sector or segment 55 is mounted. The sector 55 is adapted to mesh for addition with the drive pinion 56 and for subtraction with another drive pinion not shown, the pinion 56 being splined on the shaft 57 of the cross master wheel 58, said shaft journaled in the frame plates 15 and 17, all as heretofore. The two differential shafts are driven in unison by a linkage situated between the plates 14 and 15 and comprising an arm 60 fast on the right-hand end of shaft 44, an arm 61 fast on the left-hand end of shaft 54 and a connecting link 62.

All the parts above referred to perform substantially the same functions as heretofore.

The differential shaft 44 has heretofore had a plain bearing in each of the frame plates 11 and 14 and has been supported at the frame plate 13 by having mounted thereon a plain bearing sleeve. It is necessary that this shaft move with considerable precision because its function is to turn the master wheels 52 and 58 as exactly as possible a definite number of tooth-spaces, depending in each instance on the value of the numeral key operated. It is necessary at the same time that this shaft turn quite freely because it is operated rapidly by the down stroke of a typewriter key. I have therefore mounted this shaft on ball bearings by means well adapted for this situation.

The shaft 44 has on its left-hand end and secured thereto in any suitable way, a ball bearing member 72 which, for the want of a better term, I shall call a cone. Said shaft as shown in Fig. 4, has its left-hand end tapered beginning with the line 71 and inserted forcibly in a tapered opening in said member or cone. The balls 73 run on a suitably shaped part of the cone 72 and also in an internal groove of suitable form in a ring 74 secured in a special plate 75 which plate is fastened by two screws 76 to the outside of the frame plate 11 where it is located accurately by dowels 77. The plate 11 itself is cut away as shown in Fig. 2 into such a form as to support the plate 75 but so as itself not to touch the shaft 44 or its bearings. The ring 74 may be secured in the plate 75 in any suitable way but I prefer to make said ring peripherally with a slight taper and to force it under pressure into the plate 75. The sleeve or cone 72 is prolonged leftward so as to project out beyond the ring 74 where it is made with a peripheral groove into which a wire ring 78 is sprung so as to prevent relative motion between the parts 72 and 74 to a sufficient extent to allow of spilling the balls 73.

Near its right-hand end where the shaft 44 passes the plate 14 said shaft has another cone 80 mounted thereon, this one being in all respects like cone 72 except that it is not internally tapered, but has a fairly snug fit on the shaft. It has balls 81 running between said cone 80 and a ring 82 which ring is similar in all respects to the ring 74 and is similarly secured by a force fit in a special plate 83 which is secured to the plate 14 by means of screws 84, Figs. 1 and 3, the plate being located accurately by means of dowels 85. Cone or sleeve 80 projects rightward through the ring 82 and is provided with a retaining wire 86 like the wire 78. The cones 72 and 80 face in op-

posite directions and the two bearings may be said to be opposed meaning that the rightward pressure on one bearing is in the nature of a reaction of the leftward pressure on the other.

A collar 87 is mounted on the shaft 44 just inside the cone 80, and is secured to said shaft in any suitable way, preferably by being made like a clamp or split hub, the projecting arms of which can be drawn together by means of a screw 88, Fig. 1.

In practice the shaft 44 with all of the devices that it carries, together with its two ball bearings including not only the cones 72 and 80 and rings 74 and 82 but also the two special plates 75 and 83, are all made up as an assembly unit which can be inserted into the machine with precision under the guidance of the dowels 77 and 85 and secured in place by the screws 76 and 84.

The ball bearings are adjusted as follows: The shaft 44 is pressed lightly toward the left so as to tighten the bearings 72, 74 and the collar 87 is slid toward the right under a suitable degree of pressure, pushing the sleeve 80 before it so as to bring about a firm contact between said sleeve 80, the balls 81 and the ring 82. Holding the parts in this position the clamp screw 88 is tightened, leaving the ball bearings at the two ends of the shaft pressed into snug engagement. This will make the bearings a little too tight and special means are provided to relieve them to exactly the right extent. In the particular form shown in the drawings and which I prefer to use, this means consists of an adjusting screw 90, Figs. 2 and 4, threaded through the frame plate 11 and bearing at its inner end against the bracket or lug 18.

After the bearings have been put in place and adjusted by the collar 87, as above described, this screw 90 is turned with a screw driver against the lug 18 which slightly springs the plate 11 away from said lug. As all of the parts under consideration have hardened bearings the necessary extent of this springing is slight, but by cautiously turning the screw 90 a point can be reached where the shaft will be turned readily by the mere weight of the parts hanging from it. It is the work of but a few seconds to adjust the shaft so nicely that it turns with perfect freedom, offering no appreciable resistance and yet with no sensible lost motion in the bearings. Adjustment of the collar 87 is done almost instantly, requiring at most but a few seconds; and a slight cautious turning of the screw 90 completes the adjustment with almost perfect precision. The result is that the shaft turns as said above perfectly freely and with practically no lost motion and therefore it is possible to turn it with great precision and to communicate its motion to the lower rock shaft 54 with precision.

The bearings for the differential shaft 54 are exactly like those for the shaft 44 except that the taper 110 is at the right-hand end of the shaft 54 instead of the left-hand end and except further that the rings 111 and 112 of these bearings are pressed with a force fit directly into the frame plates 15 and 16 instead of into special plates. In actual manufacture these rings and cones would be made exactly the same as the corresponding parts for the other shaft in order to avoid multiplicity of different kinds of parts.

In Fig. 5, the right-hand cone having the taper 145 in it is numbered 113, the left-hand cone without taper 114 and the retaining wires 115. A sleeve 116 split on one side and provided with a clamping screw 117 is fastened on the shaft 54 just inside the cone 114 and it is adjusted and tight-

ened in precisely the same way as the collar 87 on the other shaft, and with the same result, namely, that it makes the bearings a little too tight. This tightness is relieved by the following means, Figs. 1 and 5: A rod 118 has its reduced and shouldered end projecting through the plate 16, the shoulder bearing against the left-hand side of said plate. At its left-hand end this rod terminates short of the plate 15 in a cone 120. A screw 121 threaded through the plate 15 has a conical depression into which the cone 120 projects. By tightening the screw 121 the two plates 15 and 16 can be sprung a very short distance apart, just enough to relieve the excess pressure on the bearings so as to make the shaft turn with perfect freedom but not enough to allow of any sensible lost motion in said bearings. It will be perceived that this shaft can be mounted and adjusted with the utmost precision in a very brief space of time.

Inventions that are shown in the drawings of this application but not claimed herein, are described and claimed in the original application of which this is a division, and in another application which also is a division of said original application.

Various changes may be made without departing from my invention.

What I claim as new and desire to secure by Letters Patent, is:—

1. In a computing machine, the combination of a shaft having opposed ball bearings, means to secure said bearings to said shaft and framework and including means adjustable to apply an excess of pressure to the bearings, and an adjust-

ing screw acting on the stationary framework in which said shaft is mounted to spring said framework to relieve such excess of pressure.

2. In a computing machine, the combination of a shaft having opposed ball bearings, each of said bearings comprising a member on the shaft and a member on the stationary framework, one of said members being slidable to a position to put an excess of pressure on the bearings, means to secure said member in such position, and adjustable means to spring the framework to relieve such excess of pressure.

3. In a computing machine, the combination of a shaft having a ball bearing cone fixed thereto and an opposed cone slidable thereon, rings in the supporting framework for cooperation with said cones through bearing balls, a collar slidable on said shaft in contact with said slidable cone, means to secure said collar in position when it and its contiguous cone have been adjusted to put an excess of pressure on said bearings, and adjustable means acting on said supporting framework to spring the latter to relieve such excess of pressure.

4. In a computing machine, the combination of a shaft, opposed ball bearings for said shaft comprising bearing members secured to the framework and bearing members secured on said shaft, means whereby one of said bearing members may be adjusted and secured in place under an excess of pressure, and means for effecting a fine adjustment of the bearings by springing the framework to relieve the excess of pressure.
